CABLE-GRIPPER

Edmund F. Dwight, Portsmouth, N. H.

Application March 24, 1937, Serial No. 132,873

11 Claims. (Cl. 104—218)

This invention relates to cable-cars and is concerned with gripper mechanism by which a car may be operatively connected to and released from a cable. The invention is herein illustrated as designed to expedite the dispatch of cable-cars of the type commonly employed to convey coal from a station near a vessel to points of discharge in a coal-yard.

In one type of conveyor system for the purpose above mentioned, the cars are towed individually around a circuit by an endless cable that provides an inbound stretch and an outbound stretch both arranged to run past the loading station. The portion connecting these stretches forms a loop and runs over one or more driving drums or sheaves.

In such a system two attendants have heretofore been required to perform the necessary routine at a loading station in the short interval of time allotted to each car. This is because a large share of the time has been required to open the grips, transfer them from the inbound stretch to the outbound stretch of the cable, set them up far enough to confine the outbound stretch without clamping it, and finally to set them up tightly to apply the necessary clamping pressure. In addition to these items of duty the routine required at the loading station includes applying the brakes and opening and closing a gate to discharge a load of four tons, more or less, from a chute into a standing car.

With a view to expediting the routine at a loading station, and thereby releasing one of the attendants for duty elsewhere, the present invention provides an improved outboard gripper mechanism capable of being operated much more rapidly and with more certainty of control than the gripper mechanisms heretofore provided for similar use. In consequence of the improvements hereinafter described and claimed, one attendant may readily perform all the aforesaid duties at a loading station without requiring any more time than two attendants have required when operating with gripper mechanisms of former construction.

One novel feature of the invention consists in an improved gripper mechanism comprising an operating member having an operating surface that includes a steep quick-acting camming portion, a shoulder and a land tangent to the shoulder. The land is arranged to maintain a certain predetermined clamping relation of the grips, the shoulder is arranged to establish that relation, and the quick-acting camming portion is arranged to effect the major relative movement of

the grips without quite setting them to clamp the cable. This latter function is utilized to confine the cable loosely in the grips so that it will surely be under control when the time comes to send the car on its way.

Another novel feature consists in an improved combination including a locking or latching member for maintaining one or more predetermined relations of the grips. As herein illustrated, this latching member is carried by the operating member and is arranged to perform its latching duty by co-acting with a cam-follower against which the aforesaid operating surface acts. To utilize the latching member for two purposes it is provided with two shoulders in series, one to prevent relative releasing movement of the grips when they are set to confine the cable loosely, and the other to prevent such releasing movement when they are set to clamp the cable.

Still another novel feature of the invention consists in an organization in which the weight of one of the grips, when applied to the aforesaid quick-acting portion of the operating surface, will furnish all the force necessary to open the grips and shift the operating member to a corresponding position at one limit of its range of operating movement.

Referring to the drawing,

Fig. 1 is a top-plan view of the rear end of a car provided with cable-gripping mechanism embodying the present invention;

Fig. 2 is a rear elevation of a car so equipped;

Fig. 3 is a rear elevation of the cable-gripping mechanism on a larger scale.

Fig. 4 is a horizontal section indicated by line IV—IV in Fig. 3;

Fig. 5 is a horizontal section in the plane indicated by line V—V in Fig. 3;

Fig. 6 is a vertical section of the platform structure that provides a mounting for the gripper mechanism, the plane of the section being indicated by line VI—VI in Fig. 2 but some of the parts of the gripper mechanism being omitted;

Fig. 7 is a vertical section of a sleeve that acts as a part of the female grip when the parts are assembled in their co-operative relation;

Fig. 8 is a perspective view of a locking or retaining member intended to surround the upper portion of the sleeve shown in Fig. 7;

Fig. 9 is a perspective view of an operating member intended to surround the lower portion of the sleeve shown in Fig. 7; and

Fig. 10 is an elevation of the parts otherwise represented in the upper portion of Fig. 3, the

essential difference being that the operating member in Fig. 10 occupies an intermediate position in its range of operating movement.

The car, incompletely represented in Figs. 1 5 and 2, is of a type commonly employed in coal-yards to which coal is transported in vessels. To avoid obscuring the mechanism with which the present invention is concerned, certain non-related parts of the car are omitted, and only the 10 lower portion of the coal compartment or body 10 of the car is represented. The wheels 11, of which one pair appears in Fig. 2, run on rails 12. An endless cable for towing cars runs between the rails 12. According to common usage the track, 15 comprising the rails 12, is laid out to provide an endless circuit in which a series of cars are conveyed individually to carry coal from a loading station adjacent to a vessel to various points along the circuit where they discharge their loads. 20 Moreover, the power-plant (not shown) for driving the cable is commonly situated adjacent to the loading station, and a loop is formed in the cable which runs from the outbound side of that station to and around the driving sheaves of the 25 power-plant and thence back to the track at the inbound side of the station. This loop provides two parallel stretches of the cable that run side by side for a short distance approaching and leaving the loading station. Consequently, the 30 gripper mechanism with which each car is equipped may be transferred from the inbound stretch of the cable to the outbound stretch while the car is coasting to its loading position at the loading station.

35 The stretch 14 of the cable represented in Figs. 1 and 2 may be regarded as the inbound stretch at the loading station, and the stretch 15 may be regarded as the outbound stretch. The gripper mechanism hereinafter described is mounted on a horizontal platform 16 attached to the rear 40 end of a car. As each car approaches the loading station an attendant operates the gripper mechanism to release it from the inbound stretch 14 of the cable, shifts the grips from the inbound stretch to the outbound stretch, operates the gripper mechanism to an extent sufficient 45 only to confine the outbound stretch loosely in the grips, operates the brake mechanism (not shown) with which each car is equipped, loads the car, and finally operates the gripper mechanism to set the grips tightly on the cable.

50 To enable one attendant to perform all the duties that have hitherto required two attendants at a loading station, the gripper mechanisms must be capable of being operated much more rapidly than any heretofore provided, and at the same time the individual stages of their operation must be definitely controlled so that guesswork and faulty or haphazard manipulation 55 will be eliminated.

With these considerations in view the present invention provides the improved gripper mechanism about to be described. The mounting of the gripper mechanism is herein represented as 60 of well-known type and will be described first.

The platform 16 is affixed to the lower surfaces of a pair of parallel supporting beams 17 extending lengthwise of the car and projecting to the rear from the rear wall 18 of the load compartment. A large hole 19 in this platform 16 permits the gripper mechanism to extend therethrough with ample clearance for all the movements of which it must be capable. This hole 19 is covered by a circular disk or turntable 20 75 of thick sheet steel, the margin of which over-

laps the rim of the hole 19 and is supported thereby. The turntable is maintained in its operative position by a series of flanged guide-rolls 21 attached to the platform 16 by pivot pins 22 (Fig. 6). The flanges of the rolls 21 overlap the 5 rim of the disk 20 to prevent the latter from being dislodged from the platform.

The central portion of the disk 20 is cut out to form a hole 23 through which the gripper mechanism may hang. At opposite sides of this 10 hole horizontal bearing blocks 24 are affixed to the upper surface of the disk 20 to receive cylindrical trunnions 25 that project in opposite directions from the male grip 26 of the gripper mechanism. Thus, to enable the grips to follow 15 the cable around curves, the described mounting provides not only for angular movement of the gripper assemblage about the horizontal axis of the trunnions 25 but also for independent turning movement of the gripper assemblage and 20 the disk 20 about a vertical axis intersecting the center of the disk.

Referring now to the construction of the gripper mechanism and particularly to Figs. 3 and 6, the male grip 26 is provided at its upper end with 25 a flat horizontal seat 27 and at its lower end with a slightly concave gripping surface 28 for engagement with the cable. The female grip comprises a lower member 30, a cylindrical stem 31, a cylindrical sleeve 32 (Fig. 7) and nuts 33 and 34 screwed on the upper end of the stem 31. The nut 33 rests on the upper end of the sleeve 32 and provides for relative adjustment of the grips to regulate the pressure with which they may clamp the cable. The lower end 35 of the member 30 has 35 the shape of a hook and is provided with a concave surface 36 arranged to co-operate with the surface 28 to grip an interposed cable. A washer 48 between the nuts 33 and 34 is provided with an internal tongue (Fig. 4) arranged to slide in 40 a groove 49 in the stem 31.

The male grip 26 remains at a constant level with respect to the car but the female grip is movable up and down to grip and release the cable. In Fig. 3 the female grip is represented 45 in solid lines as in its position of full release, that is, at the lower limit of its range of vertical movement. When in this position the entrance or gap between the grips exceeds the diameter of the cable which may, therefore, be inserted and 50 removed laterally. Dotted lines in this figure represent a semi-closed position of the female grip in which the gap is less than the diameter of the cable. This semi-closed position is established at one stage to confine the outbound 55 stretch of the cable loosely so that it may not escape accidentally but still run freely between the gripping surfaces 28 and 36 while the car is coasting and standing still.

As shown in Fig. 5 grooved guides or cheeks 37 60 formed on the member 30 loosely embrace opposite margins of the member 26 to maintain the grips in co-operative relation with freedom for relative gripping and releasing movement.

For assembling purposes, the stem 31 is inserted 65 into a bore in the member 30 and is secured to the latter by a pin 38, but before this connection is made the stem is preferably inserted through a ball-thrust-bearing 39 and then through a bore in the head of the male grip 26 70 between the trunnions 25. The thrust-bearing 39 will then be seated on the surface 27 (Fig. 6) of the male grip to support the female grip and to sustain the gripping pressure when the female grip is set up against the cable. Above the 75

thrust-bearing 39 the stem 31 is provided with a cylindrical portion 40 of relatively large diameter adapted to occupy the chamber 41 in the sleeve 32 (Fig. 7) with freedom for relative adjustment. Before the cross-pin 42 is inserted through the sleeve 32, the lower end of the sleeve is inserted through a locking or latching collar 43 (Fig. 8), this collar then having a bearing on the sleeve and being loosely confined between the pin 42 and a retaining flange 44 at the upper end of the sleeve. This flange and the cross-pin are spaced apart to permit limited relative up-and-down movement of the collar 43 for a purpose hereinafter described.

The lower portion of the sleeve 32 provides a cylindrical bearing for an operating member comprising a barrel portion 45 and an operating handle or lever 46 projecting spoke-wise therefrom. The lower end of the barrel portion is seated on the thrust-bearing 39, if one is provided, but, if desired, the thrust bearing may be omitted, in which case the barrel portion of the operating member may be extended to engage the seat 27 of the male grip 26. When the operating member 45, the sleeve 32 and the locking collar 43 have been assembled on the stem 31, the cross-pin 42 will be inserted not only through the sleeve but also through a slot 47 in the portion 40 of the stem. The slot 47 is elongated vertically to provide for adjusting the female grip to regulate its maximum gripping pressure. When the parts are thus assembled, rolls 50 are placed on the projecting ends of the cross-pin 42 to provide diametrically opposite cam-followers. The cross-pin is bored to receive cotter-pins, as shown in Figs. 3 and 10, whereby the rolls are maintained in co-operative relation to duplicate operating surfaces formed on the upper end of the barrel portion 45.

Although the functions of the operating member 45 require only one operating surface, the duplex construction about to be described is preferred for the reason that it divides and balances the load between the two operating surfaces and enables the stem 31 to slide up and down in the bore of the male grip 26 without appreciable friction. As shown in Figs. 3, 9 and 10, the duplicate operating surfaces comprise steep, quick-acting camming portions 52, horizontal lands 53 and shoulders 54 tangent to both. Abrupt stops 55 project upwardly from the low ends of the camming portions 52, and abrupt stops 56 project upwardly from the remote ends of the lands 53. These stops co-operate with the cam-followers to limit the extent of turning movement of the operating member 45 to an angle of about 90°.

When the operating member is moved clockwise as viewed in Fig. 1, from the position shown in Fig. 3 to that shown in Fig. 10, the steep camming portions 52 raise the female grip from the full-open position to the semi-closed position represented in dotted lines at the lower end of Fig. 3, this movement of the female grip being insufficient to apply clamping pressure to the cable and involving no load except the weight of the female grip. Further turning movement of the operating member in the same direction will carry the shoulders 54 under the cam-followers to effect actual clamping of the cable, but at this stage the curvature of the cam-followers and their individual rotation on the cross-pin 42 will counteract the supplemental load incidental to compressing and clamping the cable, so that no great effort on the part of the operator will be required. Once the lands 53 are brought into

load-sustaining positions little effort is required for the final stage of movement.

The latching or locking collar 43 also embodies duplicate features of construction by which it is enabled to co-operate with the cam-followers, first to maintain the operating member in the intermediate position shown in Fig. 10, and thereafter in the final position in which both the lands 53 and the arresting shoulders 56 will be in engagement with the followers. The locking collar 43 is so connected to the operating member 45 as to turn back and forth therewith, but is also free to slide up and down on the sleeve 32, to the end that the force of gravity will operate automatically to render it effective for both purposes above mentioned. A forked lever 60 (Figs. 3 and 4) straddles the collar 43 and is provided with trunnions 61 that project into aligned bearing sockets 62 (Fig. 8) bored in the collar at diametrically opposite points. This lever is carried by and located between a pair of ears formed on the handle 46 (Figs. 1 and 2) and is connected thereto by a fulcrum pin 63. If desired, the collar 43 may be guided by parallel pins affixed to and projecting upwardly from the barrel 45. The collar is provided with bores to slide on these pins. The outer end of the lever 60 serves as a handle and is so related to the main operating handle 46 that both may be grasped in one hand to lift the locking collar 43 and to open the grips.

As shown in Fig. 8 the collar 43 is provided with duplicate series of stops or abutments 65 and 66 in stepped relation, and with connecting lands 67. The stops 65 are preferably undercut or back-pitched as shown. The collar normally rests by the force of gravity on the cam-followers 50. When the parts occupy the positions shown in Figs. 2 and 3 the collar is of no effect, but when the operating member is turned to the intermediate position shown in Fig. 10, the undercut abutments 65 drop behind the followers to maintain the female grip in the semi-closed position represented by dotted lines at the lower end of Fig. 3, so that a cable may run freely between the grips and yet not escape from their embrace. Although, at this stage, the load on the steep portions 52 of the operating surfaces applies a considerable torque to the collar 43, the guide-pins 57 and the trunnions 61 (Fig. 4) are relieved of the torsional stress by the abutments 55 of the operating member and the counterparts of the collar 43 that lie against them. Moreover, since the abutments 65 are undercut, their pressure against the cam-followers applies a component of downward force to the collar 43 supplemental to the force of gravity. Consequently, the tendency of the operating member to let the female grip down actually secures the collar more firmly in its latching position to guard against accidental release of the operating member.

Fig. 1 represents the operating handle 46 in its three positions of dwell, indicated respectively at A, B and C, position C corresponding to that shown in Fig. 3, position B corresponding to that represented in Fig. 10, and position A being the gripping position at which the handle stands when the car is being towed by the cable. As each car approaches the loading station, the attendant will advance to meet it, step behind it, shift the handle from position A to position C to release the cable, and bear down on the operating handle to swing the gripper mechanism on its trunnions 25 far enough to carry the female grip over and beyond the outbound cable 75.

15. He will then place the outbound cable in the hooked end of the female grip and swing the operating handle from position C to position B, thereby raising the female grip to its semi-closed 5 position indicated by dotted lines at the lower end of Fig. 3. This semi-closed position will be automatically maintained by the stops 65 of the locking collar 43 as illustrated in Fig. 10.

These duties performed, the attendant now 10 has ample time in which to apply the brake, if necessary, and to operate the gate of the loading chute to discharge a load of four tons, more or less, into the standing car. Having loaded the car and closed the loading gate, the attendant 15 still has sufficient time in which to complete the closing movement of the female grip by shifting the operating handle 46 from position B to position A before the next succeeding car is within striking distance. At this stage the 20 operator will preferably exert at first only enough effort to effect a gradual starting of the car since it is not desirable to load the cable too suddenly. Accordingly, after the gripping pressure has been set up sufficiently to start 25 the car slowly, the attendant has merely to apply a final thrust to complete the movement of the operating handle to position A, and since the car will now be traveling its forward progress will furnish components of force and movement 30 counter to the final effort of the attendant. These opposing factors of force and movement will expedite the final stage of operation whereby the handle 46 is shifted to its trailing position indicated at A.

35. Having thus described the invention, what I claim as new and desire to secure by Letters Patent of the United States is:

1. A cable-gripper comprising a male grip and a female grip having connecting portions by 40 which they are co-operatively related, one of said grips having a cam-follower and the other having a seat facing the latter and an operating member arranged to act on said seat and said cam-follower for relatively moving them to 45 clamp, unclamp and release a cable, said operating member having an operating surface comprising a steep quick-acting camming portion, a shoulder and a land tangent to the latter, said land being arranged to maintain a certain predetermined clamping relation of the grips, said shoulder being arranged to establish said relation, and said steep portion having a range sufficient to provide for lateral insertion of a cable 50 between the grips.

55. 2. A cable-gripper as defined in claim 1 in which the operating member is sustained in its operative relation to one of said grips by the other grip.

60. 3. A cable-gripper as defined in claim 1 in which the operating member comprises a cylindrical barrel arranged to be turned about its axis and provided with duplicate operating surfaces the corresponding points of which are diametrically opposite one another, said duplicate surfaces being arranged to effect relative clamping 65 movement of the grips.

4. A cable-gripper comprising a male grip and a female grip having one a stem and the other a bearing in which said stem is arranged to slide, a cross-pin intersecting said stem and projecting radially therefrom at points spaced from said bearing, cam-rolls arranged on the projecting portions of said cross-pin, and an oper- 70

ating member having a barrel portion surrounding said stem between said bearing and said cam-rolls, one end of said barrel portion engaging said bearing, and the other end having duplicate operating surfaces arranged to operate against 5 said cam-rolls to effect relative clamping movement of said grips in consequence of turning movement of said barrel portion about the axis of said stem.

5. A cable-gripper as defined in claim 4 and 10 comprising also a sleeve surrounding said stem and engaging said cross-pin to transmit the operating movement thereof to the stem, and means for relatively adjusting said sleeve and said stem to regulate the maximum clamping pressure applicable to the grips by said operating member.

6. A cable-gripper as defined in claim 4 and comprising also a sleeve surrounding said stem and extending into said barrel portion to provide a bearing for the latter, said cross-pin intersecting, and having bearings in, said sleeve to transmit operating movement thereto, and an abutment on said stem against which said sleeve abuts to transmit said operating movement, said abutment being adjustable with respect to said stem 25 to regulate the maximum clamping force applicable to said grips by said operating member.

7. A cable-gripper as defined in claim 1, in which the elements are so organized that the weight of one of said grips, when applied to said 30 camming portion of the operating surface, will open the grips and thereby shift the operating member to a corresponding position in its range of operating movement.

8. A cable-gripper as defined in claim 1, in 35 which one of the grips is provided with a projecting cam-follower to cooperate with said operating surface, and in which a latching member is carried by said operating member to cooperate with said follower to prevent relative opening 40 movement of the grips.

9. A cable-gripper as defined in claim 1, in which a latching member is carried by said operating member and provided with a series of shoulders arranged to cooperate successively with 45 said follower to prevent relative opening movement of the grips.

10. A cable-gripper as defined in claim 1, in which the operating member consists of a barrel portion and an operating handle projecting 50 spoke-wise therefrom, said operating surface being at one end of said barrel portion and the opposite end thereof being sustained by an anti-friction thrust-bearing on said seat.

11. In a cable-car of the type in which an out-board gripper mechanism is arranged to be operated by an attendant standing on or beside the track, an operating member for said mechanism arranged to be turned about an axis through a limited range of virtually ninety degrees, said 60 member having a barrel portion and an operating handle projecting spoke-wise therefrom, and cooperative grips by which said operating member is carried, said grips having one a cam-follower and the other a seat for one end of said barrel portion, and the other end of said barrel portion having an operating surface comprising a steep quick-acting camming portion by which the grips are relatively moved, and a land arranged to maintain a certain predetermined pressure of the grips on the cable. 65 70
